UNITED STATES PATENT OFFICE

2,592,072

GAS BY-PASS FOR CRUDE OIL STORAGE
TANKS

Wilburn C. Sanders, Grandview, Tex.

Application August 26, 1947, Serial No. 770,705

1 Claim. (Cl. 137—69)

1

This invention relates to crude oil storage tanks, and more particularly to the construction of the test pipes thereof, the primary object of the invention being to provide means whereby the gas fumes which are liberated from the tank when the usual gauge opening cover of the pipe is removed, will be liberated at a point above the head of the person gauging the oil level, thereby protecting the person against the ill effects caused by breathing the gas fumes, during the gauging operation.

Another object of the invention is to provide a valve which is controlled by the operation of a foot pedal, leaving the gauger's hands free to manipulate the usual gauge line in one hand, and a gauge line wiping cloth in the other hand.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing:

Figure 1 is a front elevational view of the gauge pipe of an oil storage tank.

Figure 2 is a side elevational view thereof.

Figure 3 is a vertical sectional view through one of the valve members of the pipe.

Referring to the drawing in detail, the reference character 5 indicates a storage tank designed for storing crude oil, the tank being provided with the usual test pipe 6 that rises therefrom and communicates with the tank.

Secured to the test pipe 6, is the valve housing 7 into which the lower end of the pipe section 8 of the attachment extends, the pipe section 8 forming an extension of the test pipe 6.

Connected with the upper end of the pipe section 8 is the pipe section 9 which extends rearwardly, as clearly shown by Figure 2 of the drawing, to the upper end of which pipe 9 is secured the pipe section 10, which is of a length to discharge fumes above the head of the person making the test, thereby eliminating the ill effects caused by the gauger breathing the gas fumes during the gauging operation.

The pipe section 9 is formed with a gauge line 11, which is normally closed by means of the hinged closure 12 that is held to its closed position, by means of the coiled spring 13.

The gauge line opening 11 is in a line with the valve 14, which is secured to the shaft 15

that extends through the side wall of the valve housing 7, the valve 14 including the valve member 16 that seats against the valve seat 17 formed within the valve housing 7. A slot 12' is formed adjacent to the opening 11, through which the gauge line, not shown, moves when the closure 12 is in its closed position, during gauging.

Thus it will be seen that due to this construction, the valve member will normally close the opening through the valve housing 7. Connected with the shaft 15 at a point exteriorly of the valve housing 7, is the link 18 that has pivotal connection with the link 19 which connects with the arm 20, the arm 20 being pivotally connected with the test pipe 6 at 21. Formed on one end of the arm 20 is the pedal 22, which when pressed downwardly, causes the links 18 and 19 to swing upwardly, moving the valve 14 to its open position. The weight 23 which is secured to one end 20 of the arm 20 acts to return the valve 14 to its closed position, when pressure on the pedal 22 has been relieved.

In the use of the device, the person making the test, lowers the test line and weight, through 25 the guide line opening 11, the hinged closure 12 having been moved to its open position. As the guide line moves downwardly, it will rest on the valve member 16, and when the gauger considers that the desired length of line has been deposited 30 within the pipe section 8, he will allow the hinged closure 12 to move to its closed position. The gauger now moves the valve member 14 to its open position by pressing the pedal 22 downwardly, whereupon the line will move into the 35 tank, the crude oil collecting on the line indicating the level of the crude oil within the tank.

During the period when the line is passing from the valve member 16 to the bottom of the tank, the gas fumes will be liberated at the upper 40 end of the pipe section 10 at a point an appreciable distance above the head of the gauger, to the end that the gauger will be subjected to the ill effects caused by breathing gas fumes liberated from the usual test pipes of storage tanks.

45 The reference character 24 indicates a hook on which an electric lantern or flash light may be hung, while the test is being made in the dark.

Having thus described the invention, what is claimed is:

A test pipe for attachment to an oil storage tank comprising a valve housing secured on the outlet end of the test pipe, a valve seat within the housing, an outlet pipe extending into the top of the housing terminating a substantial distance above the valve seat, and through which

fumes pass when the valve is open, a shaft extending into the side of the housing, a valve secured to the shaft within said housing, engageable with the valve seat closing said outlet pipe, an arm pivotally mounted on the test pipe intermediate the ends of the arm, linkage connected between the shaft and pivoted arm, a pedal formed on one end of the arm effecting movement of the valve upon downward movement of said pedal, and a weight on the opposite end of 10 the arm for moving the arm in one direction, returning the valve to its normal closed position.

15 WILBURN C. SANDERS.
